UNITED STATES PATENT OFFICE.

BYRD L. EDDS, OF SHERMAN, TEXAS.

INTERNAL-COMBUSTION ENGINE.

Application filed June 4, 1926. Serial No. 113,653.

This invention relates to improvements in internal combustion engines and more particularly to engines of the rotating cylinder type particularly adapted for aeroplanes and the like but the improved features of construction are not limited to this type of engine.

An object of the invention is to provide an improved two-cycle engine; to simplify the construction of such engines, to provide for better distribution and compression of the explosive charge, and the expulsion of the burned gases; to avoid waste of fuel and obtain greater power and efficiency.

14 A further object of the invention is to provide an improved internal combustion engine of the rotating cylinder type; to provide an improved engine of this kind in which the stresses are more advantageously distributed and the forces exerted to avoid vibration, wear, looseness of the parts, to the end that a more simple, light weight, strong, durable smoothly operating engine of high efficiency will be afforded.

23 The invention, with other objects and advantages thereof, and the particular construction, combinations and arrangements of parts comprising the same, will be understood from the hereinafter contained detailed description, when considered in connection with the accompanying drawings, forming part hereof, and illustrating one embodiment of the invention.

In the drawings:

35 Figure 1 is an end elevation, with parts shown in section, of an engine constructed in accordance with the present invention.

Fig. 2 is a side elevation.

Fig. 3 is a detail section of the crank 40 shaft and crank case.

Fig. 4 is a detail longitudinal section of one of the cylinders and piston elements associated therewith, the main piston being shown at the top of its stroke in position for firing, and the auxiliary pump piston in charge receiving position.

Fig. 5 is a detail section on the line 5—5 of Figure 4.

Fig. 6 is a detail section on the line 6—6 50 of Figure 4.

Fig. 7 is a detail section on the line 7—7 of Figure 4.

55 The invention comprehends an engine having a main hollow fixed piston, a reciprocating cylinder slidable on the hollow

piston, and an auxiliary pump piston slidable in the inner end portion of the main piston, the reciprocating cylinder and auxiliary piston being connected for movement together. More particular, the invention 60 contemplates a rotating cylinder engine including a fixed crank shaft, a crank case rotatable about the shaft, a plurality of radially arranged pistons fixedly mounted on the crank shaft, and reciprocating cylinders slidably mounted on said pistons and operatively connected with the crank shaft.

While a specific embodiment of the invention is illustrated in the drawings, it will of course be understood that the particular construction shown may be changed and modified, and the invention embodied in other forms, as will appeal to those skilled in the art and falling within the scope of the appended claims, without departing from the spirit of the invention.

Referring to a detail description of the particular embodiment of the invention illustrated in the drawings, 1 designates a stationary shaft having a crank portion 1^a, 80 said shaft being supported in any suitable way, the same being shown provided with supporting plates 2 rigidly secured thereto. Mounted for rotation on the shaft 1 on suitable anti-friction bearings is the crank case 85 3 carrying a plurality of equally spaced radially disposed cylinder and piston power units. Referring particularly to Figures 1 and 4 of the drawings, each of said power units comprises a main hollow fixed piston 4 and a reciprocating cylinder 5 slidable thereon, the piston 4 having a head 6 and tubular part 7, and being arranged with its head 6 disposed outermost and its tubular part 7 facing inwardly toward the interior of the crank case 3 and secured at its inner 90 end thereto adjoining the wall of an opening in the crank case. The pistons 4, which may be secured to the crank case 3 in any suitable manner, are shown in the present instance provided with shouldered threaded end portions 8 engaging threaded wall portions 9 of the crank case 3. In each of the main hollow fixed pistons 4 is an auxiliary piston 10 slidable therein, said auxiliary piston 10^a facing inwardly, the auxiliary piston 10 and the cylinder 5 being connected for movement together and operatively connected to the crank portion 1^a of the shaft 1. The 100

105 cylinder 5 is a hollow cylinder disposed with its head 10^a facing inwardly, the auxiliary piston 10 and the cylinder 5 being connected for movement together and operatively connected to the crank portion 1^a of the shaft 1. The 110

reciprocating cylinder 5 and auxiliary sliding piston 10 are coupled together by a centrally disposed rod 11 extending through a tubular part 12 of the head 6 of the main fixed piston 4, said rod having shouldered threaded end portions 11^a—11^b, respectively fitting against and extending through openings in the head 5^a of the cylinder 5 and the head 10^a of the auxiliary piston 10, and being secured thereto by nuts 13—14. The nuts 14, at the inner ends of the rods 11 are provided with spaced ears 14^a to which are secured by pins 15 the outer ends of rods 16, said last mentioned rods at their inner ends being connected to a bearing spool 17 mounted for rotation on suitable anti-friction bearings on the crank portions 1^a of the shaft 1. The rods 16 are shown provided with enlarged portions 16^a on their inner ends, said enlarged portions engaging and being confined within a peripheral way or channel of the bearing spool, this construction providing for a limited peripheral movement of the inner ends of the rods 16 relatively to the spool 15.

The tubular part 12 of the head 6 of each of the main pistons 4 extends, as shown, through the head to either side thereof, the outer portion of said tubular part 11 which extends beyond the outer face of the piston head 6 being provided with ports 18 for the admission of the explosive mixture from the interior of the main hollow fixed piston 4 to the combustion chamber within the cylinder 5 outwardly of the head 6 of the fixed piston 4. 19 designates a tubular deflector part on the head 6 of piston 4 spaced from and surrounding the ports 18 in the tubular part 12. The tubular part 12 of the piston head 6 and the deflector part 19 are shown as separate parts from the piston head, the tubular part 12 having an externally threaded portion engaging a threaded opening in the piston head, and the deflector 19 being shown cup-shaped and held in position between a flange 12^a on said tubular part 12 and the outer face of the piston head 6. The ports 18 of the tubular part 12 of the piston head 6, are controlled by the rods 11, each of which has an outer section 11^a slidably fitting the tubular part 12 of the piston head 6, and an inner section 11^b of less diameter than the diameter of said outer section, the ports 18 being closed by the outer rod section 11^a until the lower end thereof has passed above said ports in the outward stroke of the cylinders 5. The outer rod sections 11^a are shown equipped with rings 20.

60 The cylinders 5 are provided with exhaust ports 21 which, as will be understood, are controlled by the fixed pistons 4. Each of the main fixed hollow pistons 4 has an inner end portion 7^a projecting within the crank case 3 and provided with a ring of

ports 22, and each of the auxiliary reciprocating pistons 10 is provided with a ring of ports 23 to register with the ring of ports 22 in the inner end portion of the fixed piston 4 and establish communication between the interior of the hollow fixed piston 4 and the crank case 3 at the end of the inward stroke of the cylinder 5 as illustrated in Figure 4 of the drawings. When the ports 23 of any of the auxiliary pistons 10 are opened in this way explosive mixture is drawn from the crank case 3 into said pistons and the interior of the fixed pistons 4, and as the auxiliary piston 10 moves outwardly toward the head 6 of the fixed piston 4, the mixture will be compressed, and at the proper time, the ports 18 of the tubular part 12 of the piston head 6 will be uncovered by the outward movement of the outer section 11^a of the rod 11, and the compressed charge will be forced into the cylinder 5 through said ports, the entering charge being directed centrally of and toward the head 5^a of the cylinder 5 by the deflector 19 and assisting in the expulsion of the spent gases of the previous charge through the exhaust ports 21 of the cylinder 5, which ports, as illustrated in the lower part of Figure 1 of the drawings are open at the time of the uncovering of the intake ports 18. On the return stroke of the cylinder 5 the exhaust ports 21 of the cylinder and the mixture intake ports 18 of the tubular part 12 of the piston head 6 are closed and the charge is further compressed between the outer face of the fixed piston 6 and the head 5^a of the cylinder for firing. Any suitable ignition or sparking mechanism may be employed, each cylinder being equipped with a pair of spark plugs 24. The explosive mixture is supplied to the crank case 3 through a passage 1^b in the shaft 1 from any suitable form of carburetor (not shown). 25 designates protector easings surrounding inner portions of the cylinder and piston units to protect the cylinder and fixed piston from dust and dirt, and to preserve a lubricated condition of said parts, the protector easings 25 being shown secured to the inner end portions of the fixed pistons 4.

Referring to Figure 1 of the drawings, at substantially the position designated A, the charge is fired in the cylinder 5 between the cylinder head 5^a and the head 6 of the fixed piston 4. The force of the explosion, acting through the connecting rod 16 and crank portion 1^a, rotates the crank case 3 moving the cylinder and piston around to positions B—C—D, in which latter position the exhaust ports 21 of the cylinder are open and the charge, which has been trapped and compressed by the auxiliary piston 10 is forced into the combustion chamber within the cylinder 5. Upon the continued rotation

of the crank case 3 and the cylinder 5 through the positions E—F back to the position A, the exhaust ports 21 and the intake ports 18 in the tubular part 11 are closed and the charge further compressed in the combustion chamber ready for firing, each of the cylinder and piston power units operating once during every complete revolution of the crank case.

10 Power may be transmitted from the engine in any suitable manner, a power shaft 26 rigidly secured to the end plate 3^a of the crank case 3, being shown for this purpose.

It will be noted that the particular construction and arrangement of parts hereinbefore set forth, provides, in a two-cycle engine, for the thorough compression of the charge and the expulsion of the spent gases, without waste of fuel, the compressed charge 15 entering the cylinder being directed centrally toward the outer end thereof, and being there held in place by centrifugal force until the exhaust ports are closed.

An extremely simple, light weight, strong, durable, smoothly operating engine of high efficiency is afforded. The use of valves and valve operating mechanism is entirely avoided. The construction is such that the strain from the explosions is inward against the 20 crank case, and the centrifugal strains from the cylinders and the heavier parts is carried by the crank shaft, thus it is possible to use a much lighter crank case, also the special connection between the outer ends of the cylinders and the connecting rod permits of the use of a much lighter construction of cylinder, and further since the only strain that is exerted on the connecting rod is tensioned, the rod not being driven back and forth by 25 opposing forces, a much lighter rod can be employed.

It will also be observed that by the special construction with the cylinders reciprocating on the fixed pistons, the expanding gases 30 for rotating the engine act in conjunction with centrifugal force in the same direction to move the cylinders outwardly. The cylinder on its inward movement is cushioned by the compression of the charge by the auxiliary piston in the chamber of the 35 fixed piston, and centrifugal force is acting on the cylinder at this time, whereby the pull is always outward on the connecting rods irrespective of what position the motor assumes, so that the connecting rods will 40 not knock even though the rod connections should not be tight, thus vibration, wear and breakage is avoided.

What I claim is:

60 1. An internal combustion engine comprising a main hollow fixed piston, a reciprocating cylinder slidable on said hollow piston, an auxiliary pump piston slidable in the inner end portion of the main hollow piston, means connecting the auxiliary piston and

cylinder for movement together, a crank shaft, a rod connection between the crank shaft and the auxiliary pump piston, exhaust ports for the cylinder, means controlling the same, means for admitting explosive mixture 70 to the main hollow piston, and a valve controlled passage between the hollow piston and the cylinder.

2. An internal combustion engine comprising a main hollow fixed piston, a reciprocating cylinder slidable on said hollow piston, an auxiliary pump piston slidable in the inner end portion of the main hollow piston, means connecting the auxiliary piston and cylinder for movement together, 75 a crank shaft, a rod connection between the crank shaft and the auxiliary pump piston, exhaust ports for the cylinder, means controlling the same, means for admitting explosive mixture to the main hollow piston, 80 a valve controlled passage between the hollow piston and cylinder, and an exterior protecting casing surrounding an inner portion of the main piston and cylinder.

3. An internal combustion engine comprising a main hollow piston, the head of said piston having a tubular part extending therethrough to either side thereof, a reciprocating cylinder slidable on said hollow piston, an auxiliary pump piston slidable in 90 the inner end portion of the main hollow piston, a rod connecting the pump piston and the cylinder for movement together, said rod extending through and having a portion slidably fitting said tubular part of the main piston head, a rod connection between the crank shaft and the cylinder and auxiliary piston, exhaust ports for the cylinder, means for controlling the same, means for admitting explosive mixture to the main hollow piston, 95 and a valve controlled passage between the hollow piston and cylinder.

4. An internal combustion engine comprising a main hollow fixed piston, the head of said piston having a tubular part extending 100 therethrough to either side thereof, a reciprocating cylinder slidable on said hollow piston, an auxiliary pump piston slidable in the inner end portion of the main hollow piston, means providing for the admission of explosive mixture to the main hollow piston, 105 ports in said tubular part of the head of the main piston, a rod connecting the auxiliary pump piston and cylinder for movement together, said rod extending through and having a portion thereof slidably fitting said tubular part of the main piston head and controlling the ports thereof, a rod connection 110 between the crank shaft and the cylinder and auxiliary piston, exhaust ports for the cylinder, and means for controlling the same.

5. An internal combustion engine comprising a main hollow fixed piston, the head of said piston having a tubular part extend- 115

- ing therethrough to either side thereof and provided with ports in the portion thereof projecting beyond the outer face of the piston head, a reciprocating cylinder slidable 5 on said hollow piston, an auxiliary pump piston slidable in the inner end portion of the main hollow piston, means providing for the admission of explosive mixture to the main hollow piston, a rod connecting the 10 auxiliary pump piston and the cylinder for movement together, said rod extending through said tubular part of the head of the main piston, and said rod having outer and inner sections of different diameter, the 15 outer rod portion of greater diameter slidably fitting said tubular part of the head of the main piston and controlling the ports therein, a rod connection between the crank shaft and the auxiliary piston and cylinder, 20 exhaust ports for the cylinder, and means for controlling the same.
6. An internal combustion engine comprising a main hollow fixed piston, the head of said piston having a tubular part extending 25 therethrough to either side thereof and provided with ports in the portion thereof projecting beyond the outer face of the piston head, a tubular deflector on the piston head surrounding said ports, a reciprocating 30 cylinder slidable on said hollow piston, an auxiliary pump piston slidable in the inner end portion of the main hollow piston, means providing for the admission of explosive mixture to the main hollow piston, a rod connecting the auxiliary pump piston 35 and the cylinder for movement together, said rod extending through said tubular part of the head of the main piston, and said rod having outer and inner sections of different 40 diameters, the outer rod portion of greater diameter slidably fitting said tubular part of the head of the main piston and controlling the ports therein, a rod connection between the crank shaft and the auxiliary piston, 45 exhaust ports for the cylinder, and means for controlling the same.
7. An internal combustion engine comprising a main hollow fixed piston, the head of said piston having a tubular part extending 50 therethrough to either side thereon, a reciprocating cylinder slidable on said hollow piston, an auxiliary pump piston slidable in the inner end portion of the main hollow piston, means providing for the admission of explosive mixture to the main hollow piston, ports in said tubular part of the head of the main piston, a rod connecting the auxiliary pump piston and the cylinder for movement together, said rod extending through 55 the end of the auxiliary pump piston, a rod connection between the inner end of said rod and

the crank shaft, exhaust ports for the cylinder, and means for controlling the same.

8. An internal combustion engine comprising a main hollow fixed piston, the head of said piston having a tubular part extending 70 therethrough to either side thereof, a reciprocating cylinder slidable on said hollow piston, an auxiliary pump piston slidable in the inner end portion of the main hollow piston, means providing for the admission of explosive mixture to the main piston, said last mentioned means including a ring of ports in the inner end portion of the main tubular piston, and a ring of ports in the pump piston to register with the last 75 mentioned ports, ports in said tubular part of the head of the main piston, a rod connecting the auxiliary pump piston and the cylinder for movement together, said rod extending through and having a portion slidably fitting said tubular part of the main piston head and controlling the ports therein, a rod connection between the crank shaft and the cylinder and auxiliary piston, 80 exhaust ports for the cylinder, and means for controlling the same.

9. An internal combustion engine comprising a main hollow fixed piston, the head of said piston having a tubular part extending 85 therethrough to either side thereof and provided with ports in the portion thereof projecting beyond the outer face of the piston head, said tubular part being in the form of a separate member having an exteriorly threaded portion detachably engaging the threaded opening in the piston head and provided with a laterally projecting portion, a cup shaped deflector member surrounding the ports of said tubular part and held clamped between the piston head and said lateral projecting portion of the rod, a reciprocating cylinder slidable on said hollow piston, an auxiliary pump piston slid able in the inner end portion of the main hollow piston, means providing for the admission of explosive mixture to the main hollow piston, a rod connecting the auxiliary pump piston and the cylinder for movement together, said rod extending through 90 the end of the auxiliary pump piston, a rod connection between the crank shaft and the auxiliary piston and cylinder, exhaust ports for the cylinder, and means for controlling the same.

10. An internal combustion engine comprising a main hollow fixed piston, the head of said piston having a tubular part extending 95 therethrough to either side thereof, a reciprocating cylinder slidable on said hollow piston, an auxiliary pump piston slid able in the inner end portion of the main

hollow piston, a rod connecting the auxiliary pump piston and the cylinder for movement together, said rod extending through and having a portion slidably fitting said tubular part of the main piston head, the rod having shouldered threaded end portions extending respectively through an opening in the end of the cylinder and an opening in the end of the auxiliary pump piston, nuts 5 on said threaded end portions clamping the cylinder and auxiliary pump piston to the rod, and a rod connected with the crank shaft and secured to the inner securing nut, exhaust ports for the cylinder, means controlling the same, means for admitting explosive mixture to the main hollow piston, and a valve controlled passage between the hollow piston and cylinder.

11. An internal combustion engine comprising a main hollow fixed piston, a reciprocating cylinder slidable on said hollow piston, an auxiliary piston slidable in the inner end portion of the main hollow piston, means connecting the auxiliary pump piston 20 and cylinder for movement together, and for connecting the auxiliary pump piston and cylinder to the crank shaft, exhaust ports for the cylinder controlled by the main piston, and a valve controlled passage between the hollow piston and the cylinder.

12. In a rotating cylinder engine, the combination of a fixed crank shaft, a crank case rotatable about the shaft, a plurality of radially arranged main hollow pistons fixedly 25 mounted at their open ends on the crank case in communication therewith, reciprocating cylinders slidably mounted on said pistons, auxiliary hollow pump pistons slidable in the inner end portions of the main pistons, means connecting each cylinder and one of the auxiliary pump pistons for movement together and with the crank shaft, exhaust ports for the cylinder, means for controlling the same, means for admitting explosive mixture for the hollow pistons, and valve controlled passages between the hollow 30 pistons and the cylinders.

13. In a rotating cylinder engine, the combination of a fixed crank shaft, a crank case 35 rotatable about the shaft, a plurality of radially arranged main hollow pistons fixedly mounted at their open ends on the crank case in communication therewith, the head of each of said pistons having a tubular member extending therethrough to either side thereof, reciprocating cylinders slidable on said hollow pistons, auxiliary pistons slidable in the inner end portions of the main hollow pistons, a rod connecting each auxiliary pump piston and one of the cylinders for movement together, said rod extending through and having a portion slidably fitting the tubular part of the main piston head, means connecting each cylinder and the auxiliary pump piston associated there-

with to the crank shaft, exhaust ports for the cylinders, means for controlling the same, means for admitting explosive mixture to the main hollow pistons, and valve controlled passages between the hollow pistons 70 and the cylinders.

14. In a rotating cylinder engine, the combination of a fixed crank shaft, a crank case rotatable about the shaft, a plurality of radially arranged main hollow pistons fixedly 75 mounted at their open ends on the crank case in communication therewith, the head of each of said pistons having a tubular part extending therethrough to either side thereof, reciprocating cylinders slidable on 80 said hollow pistons, auxiliary pump pistons slidable in the inner end portions of the main hollow pistons, means providing for the admission of explosive mixture to the main pistons, the tubular part of the head 85 of each main piston being provided with ports, a rod connecting each auxiliary pump piston and one of the cylinders for movement together, said rod extending through and having a portion slidably fitting said 90 tubular part of the main piston head and controlling the ports therein, a rod connection between the crank shaft and each of the cylinders and the auxiliary piston associated therewith, exhaust ports for the cylinders 95 and means for controlling the same.

15. In a rotating cylinder engine, the combination of a fixed crank shaft, a crank case rotatable about the shaft, a plurality of radially arranged main hollow pistons fixedly 100 mounted at their open ends on the crank case in communication therewith, the head of each of said pistons having a tubular part extending therethrough to either side thereof, reciprocating cylinders slidable on said 105 hollow pistons, auxiliary pump pistons slidable in the inner end portions of the main hollow pistons, means providing for the admission of explosive mixture to the main pistons, ports in the tubular part of the head 110 of each main piston, a rod connecting the auxiliary pump piston and the cylinder for movement together, said rod extending through and having a portion thereof slidably fitting said tubular part of the head of the main piston and controlling the ports therein, said rod extending through the end of the auxiliary pump piston, a rod connection between the inner end of said rod and the crank shaft, exhaust ports for the cylinder 115 and means for controlling the same.

16. In a rotating cylinder engine, the combination of a fixed crank shaft, a crank case rotatable about the shaft, a plurality of inner radially arranged pistons fixedly mounted 120 on the crank case, outer reciprocating cylinders mounted to slide over the inner fixed pistons, rod connections between the said outer reciprocating cylinders and the crank shaft, exhaust ports for the cylinders, means 125 130

for controlling the exhaust ports, and means for supplying explosive mixture to the cylinders.

17. In a rotating cylinder engine, the combination of a fixed crank shaft, a crank case rotatable about the shaft, a plurality of radially arranged inner hollow pistons fixedly mounted at their open ends on the crank case, outer reciprocating cylinders mounted

¹⁰ to slide on the exterior of the hollow pistons,

rod connections between said cylinders and the crank shaft, exhaust ports for the cylinders, means for controlling the exhaust ports, means for supplying explosive mixture to the cylinders, and a protecting cas-¹⁵ing for each cylinder and piston surrounding the inner portions thereof.

In testimony whereof I hereunto affix my signature.

BYRD L. EDDS.
